UNITED STATES PATENT OFFICE.

WALLACE M. GRAY, OF CINCINNATI, OHIO, ASSIGNOR TO THE AMERICAN VALVE AND METER COMPANY, OF CINCINNATI, OHIO, A CORPORATION OF OHIO.

AUTOMATIC SWITCH STAND.

Application filed January 3, 1927. Serial No. 158,538.

My invention relates to improvements in automatic switch stands for railway tracks. One of its objects is to provide an improved switch stand adapted to be thrown by hand, and also adapted to be thrown automatically by a train passing across or over the switch in one direction. Another object is to provide an improved simple and reliable apparatus for the above purpose. Another object is to provide an automatic switch stand in which the manually operated lever is not affected or moved when the switch is automatically thrown by the train. Another object is to provide an improved tensioning means or arrangement whereby the resilient strain to be overcome when the switch is thrown manually is of moderate degree, and the switch may be readily thrown by an operator of moderate strength. Another object is to confine the resilient tension upon the switch within predetermined limits of movement of the parts, taking the strain beyond such limits upon the rigid casing of the switch stand. My invention also comprises certain details of form and arrangement, and combination of components, all of which will be fully set forth in the description of the accompanying drawings, in which

Fig. 1 is a central horizontal section through an automatic switch stand embodying my improvements, taken through the casing on line 1—1 of Fig. 2.

Fig. 2 is a central vertical section through the same taken on line 2—2 of Fig. 1, and showing the switch lever partly thrown.

Fig. 3 is an end elevation of the same.

Fig. 4 is a side elevation, partly in central section of a shaft through which the switch is manually actuated, detached.

Fig. 5 is an end elevation of the member shown in Fig. 4.

Fig. 6 is a side elevation of the vertical yoke shaft detached.

Fig. 7 is a side elevation of the cam roller and its mounting member detached.

The accompanying drawings illustrate the preferred embodiment of my invention in which 15 represents the lower half of a switch stand casing and 16 represents the upper half of said casing. The casing member 15 is provided with plates 18 by means of which it is supported upon railway ties and rigidly mounted relative to the track and switch members. The two sections

of the casing are connected together by means of bolts 19.

A vertical shaft 20 having a loop shaped section 21 is journaled near its lower end in a journal bearing 22 carried by the casing section 15 and is journaled near its upper end in a journal bearing 23 carried by the upper casing member 16. At the lower end of the shaft 20 is rigidly attached thereto a crank arm 24 provided with a crank pin 65 25 to which is pivotally attached a switch actuating member 26.

A rocker arm 27 is pivotally attached to the loop shaped section 21 of the shaft 20 by means of stud shafts 28 and 29, so that 70 the rocker arm 27 is located within the loop of said shaft 20 and has a limited pivotal movement upon the stud shafts 28 and 29 relative thereto. A cam roller 30 is journaled upon a pin 31 which spans the forked end 32 of a shaft 33 which is journaled in a journal bearing in the rocker arm 27, and the end thrust of the shaft 33 is resisted by means of an annular bearing face 34 on the shaft 33 engaging an annular bearing 80 face 35 on the rocker arm 27.

A horizontal shaft 37 is provided at one end with a tubular drum 38 and a transverse cam face or cam channel 39. The exterior of the drum 38 serves as a journal support 85 for one end of the shaft 37, being mounted in a journal bearing 40 carried in two parts by the casing sections 15 and 16. The opposite end of the shaft 37 is provided with polygonal faces 41 which are designed to 90 seat in and move endwise relative to a corresponding polygonal faced recess or bore in a sleeve or collar 42. The collar 42 is non-rotatable relative to the shaft 37 and is exteriorly rotatably mounted in a sleeve or 95 collar 43. The collar 43 is threaded exteriorly into a collar 44 which is bolted to the casing sections 15 and 16 by means of a series of bolts 45. The sleeve 43 is adjustable 100 endwise relative to the collar 44 by means of its threaded relation to collar 44 and is provided with a series of notches or recesses 46, any one of which is adapted to be engaged by a screw or bolt 47 which is threaded into the outer end of the collar 44, and thereby serves to lock the sleeve 43 rigidly to its adjusted position relative to the collar 44. The outer end of the shaft 37 projects outside of the casing sections 15 and 16 and outside of the collar 43. The inner

105 110

end of the sleeve 42 is provided with a disk 50 against the face of which one end of a coiled spring 51 seats, while the opposite end of said spring seats against the 5 interior of the end section of the drum 38. A manually operable lever or crank arm 52 is rigidly attached to the outer end of the sleeve 42 outside of the sleeve 43, by means of which the shaft 37 and the arm 52 are 10 adapted to be rotated through one hundred and eighty degrees from a substantially horizontal position at one side of the casing to a substantially horizontal position at the opposite side of the casing.

15 The cam roller 30 normally occupies a position at one end of the cam recess 39 substantially as shown in Fig. 2 with opposite side faces of said roller in engagement with the raised edges 53 and 54 of the cam recess 39. This position of the cam roller 30 in the recess 39 and in engagement in the channel between the edges 53 and 54 prevents the shaft 33 which carries the roller 30 from rotating in its bearing in the crank arm 27 except when the horizontal shaft 37 and the vertical shaft 20 are relatively rotated, whereupon the shaft 33 rotates in its bearing sufficiently to permit such relative rotation of the shafts 37 and 20.

20 When the shaft 37 is rotated a half turn through operation of the hand lever 52, the roller 30 retains its position at one end of the channel 39 while the shaft 33 rotates in its bearing in the rocker arm 27, and at the 25 same time causes the rocker arm 27 to describe a partial rotation upon its centers 28 and 29, which movement of the roller 30 and rocker arm 27 causes the vertical shaft, 30, to rotate through an arc of ninety degrees thereby shifting the crank arm 24 and crank pin 25 and connecting member 26 and with them the switch members connected to and actuated by the connecting member 26, to open or close the switch, depending upon 40 the direction of rotation of the vertical shaft 20.

45 In the event that the switch actuating member and switch are in position to close the switch against an oncoming locomotive and the locomotive runs through the switch and thereby throws the switch to an open position, the movement of the switch by the locomotive serves to shift the connecting member 26 endwise, and through the crank pin 25, thereby rotates the vertical shaft 20 through ninety degrees, while the horizontal shaft 37 and hand lever 52 remain stationary. In order that the vertical shaft 20 and members connecting said shaft with the 50 switch may move without movement of the horizontal shaft 37, the cam roller 30 rides from one end of the cam groove 39 to the other end thereof during the locomotive driven partial rotation of the vertical shaft 20, climbing an inclined face 55 until the

axis of the shaft 37 has been reached and then riding down an inclined face 56 to the opposite end of the cam groove 39, or the reverse as the case may be. During this movement of the cam roller 30 over the high 70 central portion of the groove 39, the horizontal shaft 37 the drum 38 and cam 39 move endwise due to a yielding of the spring 51, and after the high point of the cam has been reached, return to their normal position. A nut 58 and washer 59 at the outer end of the shaft 37 engage the outer end of the sleeve 42 to form a positive stop and limit the endwise movement of the shaft 37. The opposite ends of the cam groove 39 75 are curved toward the roller 30 to form pockets to limit the movement of the cam roller and retain it in operative relation to the cam 39. The tension of the spring 51 upon the shaft 37 may be increased or decreased by adjusting the threaded sleeve 43 endwise relative to the sleeve 44. When the washer 59 engages the end of the sleeve 42, further movement of the shaft 37 toward the shaft 20 under tension of the spring 51 is prevented, thereby relieving the cam roller 30 and rocker arm 27 from excessive strain or tension. The arm 52 may be locked in position without interfering with the automatic operation of the switch. 80

The apparatus herein shown and described is capable of considerable modification within the scope of the claims without departing from the spirit of my invention.

What I claim is:

1. An automatic switch stand comprising a casing, a vertical shaft journaled to said casing and operatively connected to actuate a switch, a horizontal shaft journaled to said casing and movable endwise relative to said casing, means to resiliently tension said horizontal shaft against movement in one direction endwise, means to positively limit the movement of said horizontal shaft endwise in the opposite direction, a cam carried by 105 said horizontal shaft, a rocker arm pivotally attached to said vertical shaft upon an axle transversely to said vertical shaft, a cam roller carried by said rocker arm and held resiliently in engagement with the cam 110 of said horizontal shaft, whereby said vertical shaft may be actuated through the switch by a locomotive to shift the switch to open position independently of rotation of said horizontal shaft, and whereby said vertical 115 shaft may be manually actuated to shift the switch in either direction through rotation of said horizontal shaft.

2. An automatic switch stand comprising a switch stand casing, a vertical shaft journaled to said casing and operatively connected to actuate or be actuated by a switch, a horizontal shaft journaled to said casing and movable endwise relative to said casing, means to resiliently tension said horizontal 120 shaft

shaft against movement in one direction endwise thereof, means to positively limit the endwise movement of said shaft in the opposite direction, a rocker arm pivotally attached to said vertical shaft, a cam attached to and rotatable with said horizontal shaft and in engagement with the free end of said rocker arm to connect said horizontal shaft and vertical shaft in operative relation and 10 at the same time to permit said vertical shaft to rotate independently of rotation of said horizontal shaft through passage of the free end of said rocker arm across a high point on the face of said cam.

15 3. An automatic switch stand comprising a switch stand casing, a pair of shafts journaled in bearings in said casing and arranged transversely one to the other, a cam carried by one of said shafts, a rocker arm 20 journaled to the other of said shafts and having its free end in engagement with said cam and means to resiliently hold said cam and rocker arm in engagement, whereby rotation of said cam carrying shaft will cause 25 said rocker arm carrying shaft to rotate, while rotation of said rocker arm carrying shaft will cause the free end of said rocker arm to ride in one direction or another over an intermediate high point on said cam 30 without rotation of said cam carrying shaft.

4. An automatic switch stand comprising a switch stand casing, a switch actuating shaft journaled to said casing, means to operatively connect said shaft to a switch, a 35 rocker arm journaled to said switch actuating shaft, a manually operable shaft journaled to said casing and arranged transversely to said switch actuating shaft, a

cam at one end of said manually operable shaft, a spring operable axially of said manually operable shaft to resiliently hold 40 said cam in engagement with the free end of said rocker arm, means to adjust the tension on said spring, means to positively limit the movement of said manually operable shaft 45 and cam endwise of said shaft, and means exteriorly of said casing to partially rotate said manually operable shaft.

5. An automatic switch stand comprising a switch stand casing, a switch actuating 50 shaft journaled to said casing, means to operatively connect said shaft to a switch, a rocker arm journaled to said switch actuating shaft, a manually operable shaft journaled to said casing and arranged transversely 55 to said switch actuating shaft, and having a limited movement axially thereof, a cam at one end of said manually operable shaft, a first sleeve mounted upon the opposite end of said manually operable shaft to rotate 60 therewith and movable endwise thereon, a second sleeve adjustable endwise relative to said casing and in which said first sleeve is rotatably supported, a cam at one end of said manually operable shaft, a spring interposed 65 between said cam and said first sleeve to adjustably and resiliently hold said cam in engagement with the free end of said rocker arm, means to positively limit the movement of said manually operable shaft endwise 70 thereof, and means exteriorly of said shaft to partially rotate said manually operable shaft.

In testimony whereof I have affixed my signature.

WALLACE M. GRAY.
